HAND CULTIVATOR

Joseph J. Greiner, Arlington, Va.

Application March 31, 1955, Serial No. 35,295

Term of patent 14 years

(Cl. D39—1)

Fig. 1 is a perspective view looking at the hand cultivator from the top; and

Fig. 2 is a perspective view looking at the hand cultivator from a position beneath the cultivator and showing my new design.

I claim:

The ornamental design for a hand cultivator, as shown.
